UNITED STATES PATENT OFFICE.

RICHARD W. NEFF, OF CINCINNATI, OHIO, ASSIGNOR TO THE REMMERS SOAP COMPANY, OF CINCINNATI, OHIO, A CORPORATION OF OHIO.

DESIGN FOR A CAKE OF SOAP.

51,995.

Specification for Design.

Patented Apr. 30, 1918.

Application filed June 15, 1916. Serial No. 103,891. Term of patent 14 years.

To all whom it may concern:

Be it known that I, RICHARD W. NEFF, a citizen of the United States, residing at the city of Cincinnati, in the county of Hamilton and State of Ohio, have invented a new, original, and ornamental Design for a Cake of Soap, of which the following is a specification, reference being had to the accompanying drawing, forming part thereof.

The figure is a perspective view of a cake of soap, showing my new design.

I claim:

The ornamental design for a cake of soap, as shown.

RICHARD W. NEFF.
